(57) **CLAIM**

I claim the ornamental design for a sheet pile connector, as shown and described.

DESCRIPTION

FIG. 1 is a perspective view of a sheet pile connector;
FIG. 2 is a front elevational view thereof;
FIG. 3 is a right side elevational view thereof; and,
FIG. 4 is a bottom plan view thereof.
The broken line showing of the connector is for the purpose of showing boundaries and forms no part of the claimed design.
